(57) **CLAIM**

The ornamental design for a one-handed shovel, as shown and described.

DESCRIPTION

FIG. 1 is a perspective view of a one-handed shovel showing my new design;

FIG. 2 is a front view, with the rear view being a mirror image thereof;

FIG. 3 is a right side view, with the left side view being a mirror image thereof;

FIG. 4 is a top plan view thereof; and,

FIG. 5 is a bottom plan view thereof.

The broken lines depict portions of the one-handed shovel that form no part of the claimed design.
